Primary Examiner—Paula A. Mortimer[57] **CLAIM**

The ornamental design for a novelty sun visor, as shown and described.

DESCRIPTION

FIG. 1 is a front elevational view of the novelty sun visor showing my new design;

FIG. 2 is a rear elevational view thereof;

FIG. 3 is a right side view thereof;

FIG. 4 is a left side view thereof;

FIG. 5 is a top plan view thereof; and

FIG. 6 is a bottom plan view thereof; and,

FIG. 7 is a perspective view thereof.

The broken line showing of the human form in FIG. 7 is for illustrative purposes only and forms no part of the claimed design.
